Att^l.

UNITED STATES PATENT OFFICE.

ANTHONY J. BURNS, OF INDIANA HARBOR, INDIANA, ASSIGNOR, BY MESNE ASSIGNMENTS, TO BURNS-POLLOCK ELECTRIC MANUFACTURING COMPANY, OF INDIANA HARBOR, INDIANA, A CORPORATION OF INDIANA.

COMBINED LAMP AND PHONOGRAPH.

Application filed April 13, 1921. Serial No. 460,908.

To all whom it may concern:

Be it known that I, ANTHONY J. BURNS, a citizen of the United States, residing at Indiana Harbor, county of Lake, and State 5 of Indiana, have invented a certain new and useful Improvement in Combined Lamps and Phonographs, of which the following is a full, clear, and exact description, such as will enable others skilled in the art to 10 which it appertains to make and use the same, reference being had to the accompanying drawings, forming part of this specification.

This invention relates to a combined lamp 15 and phonograph, and the principal objects of the invention are to provide a lamp and a phonograph so that they can be used independently of each other or they can be detachably combined whereby the phonograph 20 is concealed within the lamp and is supported thereby so that the phonograph can be operated without necessitating the dismantling of said lamp or otherwise interfering with the functions thereof.

25 A further object of my invention is to provide a sound reproducing apparatus adapted to be removably positioned on the lamp and having a detachable horn or sound amplifier designed to be positioned within 30 the standard of the lamp when the reproducing apparatus is used in combination with the lamp and which horn, when the apparatus is used independently of the lamp, will serve as a support or standard for said 35 sound reproducing apparatus.

With the foregoing and other objects in view, my invention consists in certain novel features of construction and arrangement of parts, hereinafter more fully described 40 and claimed, and illustrated in the accompanying drawings, in which—

Figure 1 is a vertical cross section through the lamp, showing the phonograph positioned therein.

45 Figure 2 is a top plan view of the combined lamp and phonograph with parts broken away to illustrate the position of the tone arm.

Figure 3 is a detail view taken on the 50 line 3—3 of Figure 2.

Figure 4 is a detail view showing the

means for attaching the shade to the lamp.

Figure 5 is a vertical section through the lamp with the phonograph removed therefrom.

55

Figure 6 is a side elevation, partly in section, of the phonograph when used independently of the lamp.

Referring by numerals to the accompanying drawings, 10 designates the standard of 60 a table lamp, which standard is preferably bell-shaped and has its lower end raised from the table by legs 11 secured to said standard. Upwardly extending ornamental strips 12 are fixed to standard 10 and have 65 their upper ends terminating a short distance above the upper end of said standard.

Resting on the upper restricted end of the standard is the lower end of a supporting member 14, the upper end of which is 70 curved upwardly and outwardly to form a horizontally disposed portion 15 having a marginal flange 16 presented upwardly. Electric lamp socket members 17 having suitable electric connections are arranged on 75 the underside of portion 15 for the reception of incandescent bulbs of the lamp.

A shade 18 is removably supported on the lamp by means of downwardly extending projections or pins 19 which are carried by 80 inward extensions arranged on said shade and are adapted to enter apertures 20 formed in the horizontal portion 15. The supporting member 14 is secured in its position on the standard 10 by means of screws 21 which 85 are seated in the upper ends of strips 12 and have threaded engagement with the lower end of supporting member 14.

A top plate 22 having a downwardly presented marginal flange 24 is adapted to 90 be positioned on the supporting member 14 so that the marginal flange 24 of said plate surrounds the marginal flange 16 of the supporting member 14. These marginal flanges 16 and 24 are provided with coinciding apertures 16^a and 24^a, respectively. Screws 25 are seated in apertures 16^a and 24^a and hold plate 22 and supporting member 14 in assembled position. Fixed to the underside of plates 22 and adjacent the marginal flange 95 100 thereof is the upper flanged end 26 of a gooseneck tone-arm 27 which extends down-

wardly into the tubular portion of the lower end of supporting member 14. The lower end 28 of arm 27 is exteriorly threaded to receive the internally threaded upper end 29 of a bell shaped horn or sound amplifier 30 which, when screwed on the tone-arm 27, is adapted to occupy chamber formed in standard 10. Legs 31 are fixed to the lower end of horn 30 and space the lower end of said horn from the supporting surface when the horn is used as a support for the phonograph. The upper end of tone-arm 27 communicates through an aperture formed in plate 22 with the lower or fixed end of reproducer arm 32 supported on said plate and having its free end provided with a reproducer 34.

A motor support 35 is fixed to plate 22 and is provided on its underside with a motor 36 which through suitable driving connections actuates the turn-table or record holder 37 horizontally disposed above plate 22. Brackets 38 having their lower ends fixed to tone-arm 27 extend upwardly and are connected at their upper ends to plate 22, thereby reinforcing said plate and supporting the motor support 35 and the driving means mounted thereon. Plate 22 is provided with suitable needle cups 39.

When the device is used as a combined lamp and phonograph, the horn 30 occupies a position within the stand 10, in which position it is supported by tone-arm 27 which is located in the supporting member 14. Plate 22 is supported on member 14 and is locked in this position by screws 25. In order to place a record on turn-table 37, the upper part of shade 18 which is preferably hinged to the lower or stationary part of said shade, is moved upwardly to provide access to the turn-table 37 and reproducer 34. The sound waves travel downwardly through tone-arm 27 and horn 30 and leaving the lower end of horn 30 pass outwardly through the space formed by supporting standard 10 in raised position.

When it is desired to use the lamp without the phonograph or when it is desired to use the phonograph alone, horn 30 is removed from stand 10 by unscrewing it from the lower end of the tone-arm 27 after which screws 25 are removed from apertures 16^a and 24^a and plate 22 and parts supported thereby is then removed from its position on supporting member 14. When shade 18 is placed in its position on member 14, the lamp will assume its normal appearance and will be ready for use.

When it is desired to use the phonograph independently of the lamp, the lower end of tone-arm 27 is screwed into the upper end of horn 30 so that said horn will form a support for the tone-arm 27, plate 22, and parts carried thereby. Legs 31 space the

lower end of horn 30 away from the contact 65 with the supporting surface so that the sound waves may pass outwardly from horn 30.

To replace the phonograph within the lamp, horn 30 is removed from tone-arm 70 27 and plate 22 is positioned on member 14 with the tone-arm 27 extending downwardly into the tubular portion of said member. Screws 25 are screw-seated in apertures 24^a and 16^a and horn 30 is inserted into the stand 10 and screwed in position on the lower end of tone-arm 27.

When an electric motor is used to operate the turn-table, electric connections are provided which are separate from the electric lighting circuit of the lamp, so as not to interfere with the functions of the lamp when the phonograph is removed therefrom.

By virtue of the fact that the horn is not a part of the lamp stand, but is a separate 85 and distinct part of the phonograph, and not in any way connected to said lamp stand, I am enabled to form said horn of the proper design best adapted to distribute the sound waves. The relative sizes of lamp stand 90 and the horn are proportioned so as to permit the suspension of the horn within the lamp stand from the tone-arm, so that the entire phonograph is concealed and the lamp presents the appearance of a normal table 95 lamp.

My combined lamp and phonograph provides a fixture which is both ornamental and useful, and by making the phonograph detachable from the lamp, either one can be 100 used independently of the other.

I claim as my invention:

1. The combination of a lamp and phonograph comprising a lamp having a stand adapted to receive a sound amplifier of a 105 phonograph, a phonograph adapted to be detachably mounted on said lamp stand and having a detachable horn or sound amplifier suspended within said lamp stand and which horn, when removed from the lamp stand, 110 serves as a support for said phonograph.

2. The combination of a lamp and phonograph comprising a lamp stand adapted to have a phonograph horn positioned therein, a supporting member detachably mounted 115 on said lamp stand and provided with electric lights, a phonograph removably positioned on said supporting member, and a horn arranged within said lamp stand and detachably suspended from said phonograph, 120 said horn being adapted to be removed from said lamp stand to serve as a support for the phonograph when the latter is detached from the supporting member.

3. In combination, a lamp including an 125 upwardly tapered stand and a phonograph removably mounted on said stand and having an amplifier removably mounted in said

stand, said amplifier being adapted to support said phonograph independently of said stand.

4. In combination, a phonograph including a downwardly extending and outwardly flaring amplifying horn, adapted to serve as a support for a top plate mounting a turn table operating mechanism, reproducer and

tone arm, and a lamp including a stand adapted to conceal said amplifying horn and ¹⁰ to support said top plate independently of said horn.

In testimony whereof I hereunto affix my signature this 8th day of April, 1921.

ANTHONY J. BURNS.
